UNITED STATES PATENT OFFICE.

LOUIS E. KLUG, OF INDIANAPOLIS, INDIANA.

DESIGN FOR A BATTERY BOX.

Application filed July 6, 1925. Serial No. 14,001. Term of patent 14 years.

To all whom it may concern:

Be it known that I, LOUIS E. KLUG, a citizen of the United States, residing at Indianapolis, in the county of Marion and State of Indiana, have invented a new, original, and ornamental Design for a Battery Box, of which the following is a specification, reference being had to the accompanying drawing, forming part thereof.

In the drawing, Fig. 1 is a perspective view of a battery box, showing my new

design; and Fig. 2 is an enlarged fragmental detail of the diamond-marked surface of the panels.

I claim:

The ornamental design for a battery box, as shown.

In witness whereof, I have hereunto set my hand at Indianapolis, Indiana, this 3d day of July, A. D. one thousand nine hundred and twenty five.

LOUIS E. KLUG.
